UNITED STATES PATENT OFFICE.

WILLIAM C. NORCROSS, OF TERRE HAUTE, INDIANA, ASSIGNOR TO AMERICAN MOLDING MACHINE COMPANY, OF TERRE HAUTE, INDIANA, A CORPORATION OF INDIANA.

PATTERN-DRAWING MACHINE.

1,378,186.

Specification of Letters Patent. Patented May 17, 1921.

Application filed June 12, 1920. Serial No. 388,531.

To all whom it may concern:

Be it known that I, WILLIAM C. NORCROSS, a citizen of the United States, residing at Terre Haute, in the county of Vigo and 5 State of Indiana, have invented certain new and useful Improvements in Pattern-Drawing Machines, of which the following is a specification.

This invention relates to pattern drawing 10 machines and is an improvement on the machine set forth in my application filed April 24, 1920, Serial No. 376,287.

This invention, like the machine of my aforesaid application, has for its objects, 15 first, to apply the lifting means at a considerable distance from the center of the pattern board, thus insuring a steadyng action; second, to provide means for clamping the drawing head or frame to the pattern 20 board at either the sides or ends thereof; third, to provide for maintaining parallelism of the drawing frame in relation to the pattern board; fourth, to make provision for an improved mounting or application of 25 the machine to the flask whereby it is supported on the flask and special connections are obviated; fifth, to provide for adjustments to adapt the machine to any size of flask coming within its range.

30 In addition to the foregoing objects which are accomplished by the present improved machine, my present invention has for its object the provision of a simple cable and sheave arrangement combined in a novel 35 manner with the drawing frame or head and the supporting frame to which any suitable lifting means or hoist, such as used in foundries, may be applied for the purposes, first, of suspending the pattern drawing 40 machine and locating it on the flask and, second, for drawing the pattern.

While my invention carries out the general objects which I have enumerated, it differs mainly from the machine of my application Serial No. 376,287 in the provision 45 of the cable and sheave suspending and operating means which renders unnecessary the employment of a drawing cylinder and piston and the use of compressed air for pur- 50 poses of operation. In brief, with the present improvements, any lifting means or hoist used in a foundry may be utilized to position the present machine, draw the pattern and remove the machine from the flask.

The disclosure in the accompanying drawings, and which is hereinafter described, represents a practical embodiment of my invention, but, as modifications may be resorted to without departing from the essential principle thereof, such disclosure and description may be considered as illustrative, instead of restrictive, of the invention.

In the accompanying drawings,

Figure 1 is a side elevation; Fig. 2 is an end elevation; Fig. 3 is a diagram of a 65 modification, and Fig. 4 is a plan view of the machine of Figs. 1 and 2.

The upper part of the flask from which the pattern is to be drawn, appears at 1; the sand is shown at 2 and the pattern is 70 represented at 3, said pattern being attached to the usual pattern board 4 which rests upon flask 1. The flask is shown in inverted position, after it has been rammed, either 75 on a machine or by hand. Having been rammed, the flask is picked up by hand or power means and turned over or set down wherever desired, so that it will be adapted for the application thereto of the present 80 drawing machine.

My drawing machine has an upper frame 5 and a lower frame 6. The upper frame 5 has lugs 7 provided with horizontal bores. Mounted either tightly or slidably in the lugs 7 are shafts 8, which have freely projecting ends. Upright supporting posts 9 to which the respective crossheads 10 are 85 securely fastened, rest upon the top of the flask 1. It is only necessary to bore holes 11 in the pattern board 4 to allow the post 90 9 to be passed through said holes and made to rest on the flask 1, to enable my machine to be applied to a flask. There are bores 12 in each cross head which are slidably mounted on the projecting ends of shafts 95 8, thus enabling the posts 9 to be moved laterally to any position required to suit the position of the holes 11 in the pattern board of the particular flask which is to be drawn. Set screws 13 secure the cross heads 100 10 to the shafts 8.

Vertical guide posts 14 whose lower ends are securely seated in sockets 15 on lower frame 6, are slidale through vertical guides 16 on upper frame 5. The guide posts 14 105 keep the drawing frame 6 parallel to the joint of the flask, thereby insuring accurate drawing of the pattern. The lower face of

the frame 6 is machined to fit against the battens of the board 4. Stirrups 17 which are secured at 18 to the sides or ends of the board 4, are adapted to be engaged by U-5 clamps 19 which, in turn, overhang an outstanding marginal flange 20 on frame 6 and are secured by wedges 21. By these, or other suitable, devices the frame 6 is rigidly clamped on the battens of board 4 and lateral displacement of the pattern board during drawing is prevented.

Carried by the upper ends of the guide posts 14 are stop pins 22 which are adapted to engage the guides 16 to prevent the frame 6 from dropping below normal position. Holes 23 are provided in the guide posts 14 through which pins may be inserted to rest on the guides 16 for the purpose of holding the frame 6 in raised position, if desired.

20 Mounted on the frame 6 in the median plane or longitudinal axis thereof are sheaves 24. A cable 25, which has its ends secured to the ends of the frame 5 in the median plane or longitudinal axis thereof, 25 runs around the sheaves 24 and over a loose sheave 26 which has a clevis 27. The cable 25 straddles a tie bar 28 on the frame 5, the sheave 26 being located above said tie bar. The tie bar prevents sheave 26 and 30 cable 25 from dropping when not in use.

Having set the posts 9 nearer or farther apart according to the size of the flask which is to be drawn, the set screws 13 are tightened to clamp the posts 9 to the shafts 8.

35 Any suitable lifting means or hoist may be applied to the clevis 27, thereby drawing upon the frame 6 until it is against frame 5. The machine may now be lifted and placed on the flask from which the pattern is to be 40 drawn. The posts 9 having been entered in the holes 11 and made to rest upon the flask 1, the hoist is lowered until the frame 6 rests upon the battens of the pattern board 4. The clamps 19 are now applied to the 45

stirrups and the wedges 21 driven home, thereby firmly clamping the frame 6 to the pattern board 4. The hoist or lifting means is again applied to the clevis 27 and the clevis and sheave 26 raised. The upward 50

pulling of the central part of the cable 25 draws the frame 6 upwardly, the guide posts 14 sliding through the guides 16. The ends of the cable 25 being fastened to the upper frame 5, the lifting action causes the 55

posts 9 to be pressed down upon the flask 1, thus firmly holding the machine in position while the pattern is being drawn. Continued elevation of the frame 6 up to or 60 against the frame 5 finally draws the pattern from the flask. When the frame 6 engages frame 5, the entire machine is lifted from the flask and may be swung clear thereof. The pattern board and pattern are then released by knocking out the wedges 21 65 and removing the clamps 19.

To enable any flask to be drawn within the range of my machine, it is only necessary to bore the holes 11 in the pattern board 4 so that the lower ends of the posts 9 may be allowed to pass through and rest on the flask 1. By this arrangement and the use of the clamps, the pattern board is lifted at a considerable distance from its center, insuring an even draw. The adjustability of the posts 9 enables a single machine, within its range, to be made quickly applicable to any size of flask.

70 The use of the cable and sheave suspending and operating means enables the machine to be made in very simple, durable and light form and does away entirely with an expensive piston and cylinder and the use of compressed air, or other external means, beside enabling ordinary hoist or lifting devices commonly employed in a foundry to be 75 used in operating the machine.

80 As shown in Fig. 3, in lieu of the sheave 26 there may be employed an equalizing bar 26^a to whose ends the ends of the cables 25^a are connected; the clevis 27^a being connected to the central part of the bar 26^a.

90 What I claim is:

1. In a pattern drawing machine, the combination with a supporting frame and upright posts for sustaining said frame, of a slidably mounted pattern drawing frame movable up and down in relation to said supporting frame, and cable and sheave raising and lowering means for said slidably mounted pattern drawing frame.

95 2. In a pattern drawing machine, the combination with a supporting frame, of a slidably mounted pattern drawing frame, and cable and sheave raising and lowering means for said pattern drawing frame comprising an anchored cable, sheaves on the movable pattern drawing frame, and a loose suspending and lifting device, said cable running around said sheaves and to the suspending and lifting device.

100 3. In a pattern drawing machine, the combination with a supporting frame, of a movable pattern drawing frame having guide connections with the supporting frame, and raising and lowering means for said movable frame comprising sheaves on the movable frame, a loose suspending and operating device, and a cable whose ends are anchored to the supporting frame and which runs around the sheaves aforesaid, and to the suspending and operating device.

115 4. In a pattern drawing machine, the combination with an upper frame, of supporting posts therefor adapted to rest on the flask from which a pattern is to be drawn, a slidably mounted frame adapted for connection to the pattern board of the flask, and cable and sheave raising and lowering means for said slidably mounted frame.

120 5. In a pattern drawing machine, the

combination with an upper frame, of supporting posts therefor adapted to rest on the flask from which a pattern is to be drawn, a slidably mounted frame adapted 5 for connection to the pattern board of the flask, means for guiding the slidably mounted frame in relation to the upper,

supporting, frame, sheaves carried by the slidably mounted frame, a cable suspending and operating device, and a cable whose intermediate portion runs over the said sheaves and whose ends are anchored. 10

In testimony whereof I affix my signature.

WILLIAM C. NORCROSS.
